UNITED STATES PATENT OFFICE.

LEWIS THOMAS GODFREY-EVANS, OF WEST NORWOOD, LONDON, ENGLAND.

INTERNAL-COMBUSTION ENGINE.

1,414,356.

Specification of Letters Patent.

Patented May 2, 1922.

Application filed February 9, 1921. Serial No. 443,645.

(GRANTED UNDER THE PROVISIONS OF THE ACT OF MARCH 3, 1921, 41 STAT. L., 1313.)

To all whom it may concern:

Be it known that I, LEWIS THOMAS GODFREY-EVANS, a subject of the King of Great Britain and Ireland, and a resident of West 5 Norwood, county of London, England, have invented a certain new and useful Improvement in Internal-Combustion Engines, on which I have obtained Letters Patent in Great Britain No. 29,736, dated November 10 28, 1919, and of which the following is a specification.

This invention relates to internal combustion engines of the kind wherein the engine is governed by the charge of liquid fuel being measured out in accordance with the expansion pressure in the working cylinder. Heretofore, the only suggestions made for effecting this have had in view the control of the supply of explosive gas to the engine 20 cylinder. In one case the induced charge passed through a spring-pressed throttle valve, the spring-pressure on the valve being augmented by a pressure dependent on the terminal expansion pressure, the number 25 of revolutions and the escape of cylinder gases from or past a hand-regulated throttle valve, this being arranged by placing the spring and a piston on the valve in a chamber connected to the working cylinder and 30 to said hand-regulated valve.

According to the present invention, I employ a loaded valve, for example, a spring-pressed differential valve, not for throttling a previously mixed charge, but for displacing a volume of liquid fuel from its storage 35 receptacle in accordance with a pressure or range of pressures of the expansion curve, whereupon this increment of fuel passes to a carburetter to be mixed with air in any desired manner. It is equally applicable to oil 40 tanks for distributing lubricating oil to engine parts.

One embodiment of the invention is illustrated, by way of example, in the accompanying drawing, showing a fuel tank 1, enclosed but for an inlet 2 for gaseous fluid above the liquid level and an outlet 3 to the carburetter of the type shown, for example, in my co-pending application Serial No. 443,646, filed February 9, 1921. The inlet 2 for gaseous fluid is connected through a spring-pressed or equivalently loaded valve 4 to a pipe 5, which is connected to the explosion chamber of the engine, such for example as that shown in my co-pending ap-

plication Serial No. 443,644, filed February 9, 1921, at a place whereat this pipe will be subjected to a pressure or range of pressures represented by the expansion curve. The pipe 5 may contain a non-return valve, 60 such as a ball valve 12.

As seen from the figure, the device for measuring out the fuel in accordance with the expansion pressure comprises differential pistons 4, 4' which in action take up a 65 position determined by the compression spring 6. At a desired period of the stroke after the explosion has occurred, the expansion pressure is transmitted by the pipe 5 to the intermediate chamber 7. The pressure 70 in the upper chamber 8 will at this moment be less than in chamber 7. The piston 4 therefore rises and uncovers the port 9 in the cylinder wall. Gas will therefore flow into said port and so raise the pressure 75 slightly in the chamber 8 and in the space 10 above the liquid level in the fuel tank 1.

The piston 4 is so adjusted that a very small quantity of gas passes into port 9. The amount which passes will depend on 80 the pressure in the cylinder and which may be visualized by the shape of the expansion curve, and as the pressure in chamber 8 is comparatively low, it will be seen that the volume of gas passing into port 9 is roughly 85 determined by the varying expansion pressures consequent upon varying loads placed on the engine at any time.

By a suitable restriction, such as of the nozzle of the carburetter, beyond pipe 3, the 90 discharge of fuel from tank 1 will be equal in volume to the gas which enters the space 10; consequently, the fuel discharge will be in accordance with the expansion pressure or engine load. 95

To check the reciprocatory action of the pistons 4, 4', I may provide a damping device such as an oil dashpot 11. I aim at the piston 4 remaining, during the operation of the engine, as far as possible at the 100 position wherein its lower face nearly coincides with the lower edge of port 9, so that the supply of burnt or partly burnt gas can be instantaneously admitted to same. At each explosion in the working chamber of 105 the engine there may thus be injected into port 9, and therefore space 10, a volume of gas in accordance with the pressure in the cylinder and consequently with the load on the engine. 110

Moreover, to establish equilibrium quickly in the event of the load being suddenly thrown off, I may employ a by-pass 9' which will allow gas in chamber 7 to be transferred to chamber 7' below the piston 4', because the reduction in pressure in chamber 7 will result in a sudden greater difference in the pressures in chambers 8 and 7, causing the differential piston to drop sufficiently for the gas in chamber 7 to enter chamber 7' by means of said by-pass. The orifice 10' is a constricted vent, so that the piston 4' becomes balanced and thus restores the differential piston to its normal position.

15 I claim:—

1. Apparatus for governing internal combustion engines, comprising a spring-controlled differential valve, so arranged that a volume of gas determined by a pressure or 20 pressures within the cylinder of the engine at certain points in the expansion curve is allowed to pass the valve and so displace a

corresponding volume of liquid fuel from its storage receptacle in order that this fuel may be admitted to the carburetter, substantially as described. 25

2. A device for governing the supply of fuel to the carburetor of an internal combustion engine, including a valve unit having differential pistons therein, a pipe line 30 establishing communication between the combustion chamber of the engine and the space between the differential pistons in the valve, a fuel supply tank having a connection with the carburetor and a pipe line communicating with the fuel supply tank and with the valve casing, said pipe line at its point of communication with the valve casing being controlled by one of the differential pistons. 35

In testimony whereof I have affixed my signature hereto this 21st day of January, 1921.

LEWIS THOMAS GODFREY-EVANS.
